(57) **CLAIM**

The ornamental design for a toy drum, as shown and described.

DESCRIPTION

FIG. 1 is a first perspective view of a toy drum according to a first embodiment of the design.

FIG. 2 is a second perspective view of the toy drum of FIG. 1.

FIG. 3 is a front view of the toy drum of FIG. 1.

FIG. 4 is a rear view of the toy drum of FIG. 1.

FIG. 5 is a first side view of the toy drum of FIG. 1.

FIG. 6 is a second side view of the toy drum of FIG. 1.

FIG. 7 is a top view of the toy drum of FIG. 1.

FIG. 8 is a bottom view of the toy drum of FIG. 1.

FIG. 9 is a first perspective view of a toy drum according to a second embodiment of the design.

FIG. 10 is a second perspective view of the toy drum of FIG. 9.

FIG. 11 is a front view of the toy drum of FIG. 9.

FIG. 12 is a rear view of the toy drum of FIG. 9.

FIG. 13 is a first side view of the toy drum of FIG. 9.

FIG. 14 is a second side view of the toy drum of FIG. 9.

FIG. 15 is a top view of the toy drum of FIG. 9; and,

FIG. 16 is a bottom view of the toy drum of FIG. 9.

The broken lines shown in the drawings depict portions of the toy drum that form no part of the claimed design.
